Primary Examiner — Rhea Shields(74) *Attorney, Agent, or Firm* — Andrew F. Young, Esq.; Nolte Lackenbach Siegel(57) **CLAIM**

The ornamental design for a packaging container, as shown and described.

DESCRIPTION

FIG. 1 is a front top perspective view of a packaging container showing my new design.

FIG. 2 is a rear perspective view thereof;

FIG. 3 is a front elevational view thereof;

FIG. 4 is a rear elevational view thereof;

FIG. 5 is a right side elevational view thereof; the left side elevational view being a mirror image thereof;

FIG. 6 is a top plan view thereof;

FIG. 7 is a bottom plan view thereof; and,

FIG. 8 is a front perspective view in an open position.

The broken lines in FIGS. 1 to 5, and FIGS. 7 and 8 are included for the purpose of illustrating portions of the article and form no part of the claimed design. No claim is made to portions that are not shown.

1 Claim, 5 Drawing Sheets(56)
